F. H. SHARAR.
VALVE ADJUSTER.
APPLICATION FILED DEC. 8, 1919.

1,343,525.

Patented June 15, 1920.

UNITED STATES PATENT OFFICE.

FRED H. SHARAR, OF WILLIAMSPORT, PENNSYLVANIA.

VALVE-ADJUSTER.

1,343,525.

Specification of Letters Patent. Patented June 15, 1920.

Application filed December 8, 1919. Serial No. 343,256.

To all whom it may concern:

Be it known that I, FRED H. SHARAR, a citizen of the United States, residing at Williamsport, in the county of Lycoming and State of Pennsylvania, have invented a new and useful Valve-Adjuster, of which the following is a specification.

This invention relates to new and useful improvements in tappet valve construction, 10 and more particularly to valves of this character employed in connection with internal combustion engines.

The primary object of the invention is to provide means for adjusting the valve rod 15 for lengthening or shortening the stroke thereof, thus insuring a proper seating of the valve, at all times.

A further object of the invention is to provide efficient means for locking the valve 20 stem in its various positions of adjustment, thus permitting exceedingly fine adjustment to be made, and maintained.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:—

35 Figure 1 illustrates a fragmental sectional view through a valve casing, in which the valve, forming the subject matter of the present invention, operates;

Fig. 2 illustrates a detail view of the 40 thimble forming a part of the invention;

Fig. 3 illustrates a modified form of the thimble;

Fig. 4 illustrates a sectional view taken 45 on line 4—4 of Fig. 1.

Referring to the drawing in detail, the 50 reference character 5 designates the valve cage which is provided with the usual guide bore 6, which accommodates the valve rod 7 forming the important feature of the present invention.

This valve rod 7 has connection with the 55 valve proper 8, and is disposed within the bore 6 of the cage 5, the lower end of said rod extending downwardly and terminating 60 at a point directly above the bearing 9, which forms a part of the cylinder to which

the valve is applied, and as shown this bearing 9 is relatively large to accommodate the push rod 10, which is provided with a bore extending from one end thereof and 60 terminating a predetermined point adjacent the opposite end of the push rod 10, the lower end of said push rod being bifurcated as at 11, to receive the roller 12, which roller 12 contacts with the usual cam 13 provided 65 on the cam shaft 14, whereby movement of the cam shaft 14 imparts a reciprocating movement to the push rod 10, through the roller.

The bore formed in the push rod 10, is 70 preferably threaded to receive the threaded extremity 15 of the thimble 16, which thimble is divided intermediate its length by the wrench accommodating surfaces 16', the upper extremity of which thimble is shown as 75 tapered and internally threaded, for purposes to be hereinafter more fully described.

Disposed within the side walls of the upper portion of the thimble 16, are longitudinal slots 17 which are disposed diametrically opposite each other to provide a plurality of sections 18, which sections, due to the slotted portions 17 possess a degree of resiliency to permit the same to move into and out of engagement with 85 the threaded portion 19 of the adjusting screw 20.

A nut 21 operates on the upper tapered portion of the thimble 16 for moving the sections 18 into and out of engagement with 90 the adjusting screw 20. This adjusting screw 20 is provided with a knurled head 22, to permit the adjusting screw to be grasped by the four fingers of the operator to accomplish the rotation of the adjusting 95 screw to enable the same to be moved longitudinally within the thimble 16 to cause the adjusting screw to move toward and away from the thimble, at the will of the operator.

Forming a part of the adjusting screw 20, is a flattened head 23, which is of a diameter to receive the lower extremity of the valve rod 7, which is held in close engagement with the flattened portion 23 by 100 means of the coiled spring 24, which encircles the valve rod 7, and has its lower extremity seated in the cup 25 secured to the valve rod 7, the upper portion of which spring engages the wall 26, of the valve 110 cage.

From the foregoing it will be seen that if

the valve 8 becomes worn, or for other reasons does not properly seat, it is only necessary to loosen the nut 21 and rotate the adjusting screw 20 to cause the same 5 to move to lengthen, or shorten the stroke of the valve rod 7, to the end that any wear at the valve seat, or between the cam and push rod may be compensated for.

The nut 21 is now rotated to cause the 10 same to move over the double surface of the upper end of the thimble to cause the sections 18 to grasp the threaded portion 19 of the adjusting screw 20, whereupon the adjusting screw is locked in its position of 15 adjustment.

Having thus described the invention, what is claimed is:—

1. A tappet valve construction including a push rod, a thimble supported within the 20 push rod, said thimble having an upper tapered portion, said tapered portion being internally and exteriorly threaded, an adjusting screw having a threaded shank co-operating with the internal threads of 25 the thimble for securing the thimble and adjusting screw together, a nut operating on the external threads of the thimble for locking the adjusting screw to

the thimble, said adjusting screw having a head providing a seat for the valve rod, 30 and means for holding the valve rod to the adjusting screw.

2. A tappet valve construction including a valve rod, a push rod having a bore formed in the upper end thereof, a thimble positioned within the bore, said thimble having a threaded and split upper end, an adjusting screw having a threaded end co-operating with the threads of the thimble, for securing the thimble and adjusting 35 screw together, a locking nut operating on the split end of the thimble for moving the walls thereof into engagement with the adjusting screw, said adjusting screw providing a seat for one end of the valve rod, 40 and means for normally holding the valve rod into engagement with the adjusting screw.

In testimony that I claim the foregoing as my own, I have hereto affixed my signature in the presence of two witnesses.

FRED H. SHARAR.
